UNITED STATES PATENT OFFICE.

WILL H. PHILLIPS, OF CHICAGO, ILLINOIS, ASSIGNOR TO WORTHINGTON PUMP AND MACHINERY CORPORATION, A CORPORATION OF WEST VIRGINIA.

CONDENSER AND TUBE CLEANER THEREFOR.

Application filed September 13, 1920. Serial No. 410,074.

This invention relates particularly to surface condensers and means for cleaning the condenser tubes, the object being to provide a simple and practical construction by which the tubes may be cleaned frequently at small cost, without interfering with the operation of the condenser, and condenser tubes thus maintained in the most efficient condition. The invention may be applied, however, to other apparatus in which a large number of tubes are to be cleaned by water, steam, air, or other fluid.

For a full understanding of the invention a detailed description of a construction embodying the same in its most complete and preferred form will now be given in connection with the accompanying drawings forming a part of this specification and the features forming the invention then specifically pointed out in the claims.

In the drawings:—

Figure 1 is a detail section through the water chamber of a condenser showing the cleaning device in place.

Figure 2 is an enlarged view of a part of Fig. 1.

Figure 3 is a view similar to Fig. 2 with the nozzle tube withdrawn and the tube aperture closed.

Figure 4 is an outside end view of the condenser showing all the tube apertures closed as in Fig. 3.

Figure 5 is an end view looking to the right in Fig. 3.

Figure 6 is a cross section on the line 6—6 of Fig. 3.

Figure 7 is a detail section of the outer head of the cleaning tube.

Figure 8 is a detail section of the nozzle.

Referring to the drawings, the condenser A shown is of the common type having the inner tube plates B carrying the tubes C, and the outer head D, the plates B, D enclosing the water chamber through which the circulating water passes to and from the tubes C. The head or water chamber cover D is provided with a series of openings 10, the number depending upon the size of the condenser, and these openings are covered by caps 11 secured to the head in any suitable manner and packed by packing 1, so as to form a tight joint with the head. In each cap 11 is mounted centrally a ball 12 seated in an opening through the cap by rings 9, so as to form a tight joint while

free to move universally therein, and this ball 12 is provided with necks 13, 14 on opposite sides, which form supports for the cleaning tube. The outer neck 14 carries also a valve chamber 15 and outer hub 16 through which the cleaning tube is passed, the aperture in this hub being normally closed by a cover plate 17 which seats on packing 1, so as to form a tight joint, and as shown, is held in position and released for rotation to uncover the tube aperture by screw 18 and swinging bolt 19. Any other suitable construction may be used for this purpose.

The tube aperture through the hub 16 is closed on the inside by valve 20 seating on the valve seat at the inner end of the hub, this valve being shown as carried by arm 21 on rock shaft 22, which shaft carries an arm 23 to which spring 24 is attached for spring pressing the valve toward its closed position.

The cleaning tube 25 carries at its inner end a removable nozzle 2 so that the nozzle may be changed to suit varying conditions, and at its outer end a head 26 carrying handle 27 for manipulating the tube and a hose connection 28 to which a flexible hose 29 may be attached for supplying water, steam, air or other cleaning fluid. The head 26 carries, also, eyes and connecting chains or other flexible links 30, these being shown as wire links, by which the head may be connected by catch hooks 4 to eyes 5 on the caps 11, so as to hold the cleaning tube in position and prevent accidental removal therefrom when in operation while permitting proper movements.

The cleaning operation will be understood on a brief description:

When the tubes are to be cleaned, one of the covers 17 is swung away from the tube aperture in hub 16, and tube 25 is then inserted through the hub, valve 20 yielding against spring 24 as the tube is inserted, leaving a passage through hub 16, ball 12, necks 13, 14, open for the passage of the tube into the position shown in Fig. 1. Chain's 30 are now connected to eyes 5, the cleaning fluid turned on and the operator, by handle 27, swings the tube 25 by the universal joint formed by ball 12 and moves the tube longitudinally through the ball so as to clean successively the group of tubes within reach of the tube, the operation of

2
the tube being shown in Figs. 1 and 2, and the parts with the cleaning tube removed in Figs. 3 to 6.

One group of condenser tubes thus having been cleaned, the cleaning device is withdrawn from the cap 11 giving access to such group, the valve 20 closing automatically as the tube is withdrawn, and the cover 17 then being closed and secured by hand, the cleaning tube is transferred to another cap 11 giving access to another group of tubes, and this operation is continued until all the tubes are cleaned.

It will be understood that the material cleaned from the tubes passes out with the water, and that the cleaning involves no interruption in the operation of the condenser, there being no substantial water leakage past the cleaning tube, and the tube aperture being closed automatically on the withdrawal of the tube. If desired, sand or other cleaning material may be added to the fluid, and any suitable cleaning fluid may be used. It is found in practice, however, that water or steam alone, is satisfactory for condenser tube cleaning under ordinary conditions. If the cleaning device be applied to tubes other than those of condensers, the cleaning fluid or material used will depend upon tube conditions.

It will be understood that the invention is not limited to the specific construction or arrangement of parts shown as embodying the invention, but that modifications may be made therein while retaining the invention defined by the claims.

What I claim is.

1. A surface condenser having a series of tubes and a chamber outside the tube ends, the outer wall of said chamber having a series of openings arranged for the cleaning of the series of tube interiors in different groups through the different openings, in combination with a universal joint member mounted in each of said openings and having an aperture for the passage of a cleaning tube for delivery of cleaning fluid into the tubes, and means on the opposite side of the universal joint relatively to the chamber for closing the universal joint member aperture automatically on the withdrawal of the cleaning tube.

2. A surface condenser having a series of tubes and a chamber outside the tube ends, the outer wall of said chamber having a series of openings arranged for the cleaning of the series of tube interiors in different groups through the different openings, in combination with a universal joint member mounted in each of said openings and having an aperture for the passage of a cleaning tube for delivery of cleaning fluid into the tubes, means on the opposite side of the universal joint relatively to the chamber for closing each opening automatically

on the withdrawal of the cleaning tube, and means additional to said automatic closure for securely closing each opening after the withdrawal of the tube.

3. A surface condenser having a series of tubes and a chamber outside the tube ends, the outer wall of said chamber having a series of openings arranged for the cleaning of the series of tube interiors in different groups through the different openings, a universal joint member in each of said openings having an aperture for the passage of a cleaning tube for delivery of cleaning fluid into the tubes, and a closure for said aperture on the opposite side of the universal joint relatively to the chamber forming a part of the universal joint member adapted to be opened by the insertion of the cleaning tube and automatically closed on the withdrawal of the tube.

4. A surface condenser having a series of tubes and a chamber outside the tube ends, the outer wall of said chamber having a series of openings arranged for the cleaning of the series of tube interiors in different groups through the different openings, a universal joint member in each of said openings having an aperture for the passage of a cleaning tube for delivery of cleaning fluid into the tubes, a closure on the opposite side of the universal joint relatively to the chamber for said aperture adapted to be opened by the insertion of the cleaning tube and automatically closed on the withdrawal of the tube, and means additional to said automatic closure for securely closing the tube aperture after the withdrawal of the tube.

5. A condenser having a series of tubes and a chamber outside the tubes, the outer wall of the chamber having an opening, a hollow universal joint member in said opening and having an aperture for the passage of a cleaning tube, and a closure for said aperture mounted within said hollow universal joint member and outside of said chamber adapted to be opened by the cleaning tube on its insertion and automatically closed on the withdrawal of the tube.

6. A condenser having a series of tubes and a chamber outside the tubes, the outer wall of the chamber having an opening, a universal joint member in said opening and having an aperture for the passage of a cleaning tube, a closure for said aperture on the opposite side of the universal joint relatively to the chamber adapted to be opened by the cleaning tube on its insertion and automatically closed on the withdrawal of the tube, and a cover for securely closing the outer end of the universal joint member aperture after the withdrawal of the tube.

7. The combination with a wall D having an opening, of a cap 11 closing said opening, a ball 12 closing an opening in said cap and

- having an aperture for a cleaning tube, a valve chamber 14 mounted outside said cap and having a tube aperture communicating through said chamber with the aperture in 5 said ball and a valve seat surrounding the aperture in said chamber, and a spring closed valve 20 on said seat adapted to be opened by the tube on its insertion.
8. The combination with a wall D having an opening, of a cap 11 closing said opening, a ball 12 closing an opening in said cap and having an aperture for a cleaning tube, a valve chamber 14 mounted outside said cap and having a tube aperture 10 communicating through said chamber with the aperture in said ball, a valve seat surrounding the aperture in said chamber, a spring closed valve 20 on said seat adapted to be opened by the tube on its insertion, and, 15 a movable cover 17 outside the valve chamber for securely closing the tube aperture.
9. A surface condenser having a series of tubes and a chamber outside the tube ends, the outer wall of said chamber having a 20 series of openings, a universal joint member in each of said openings having an aperture for the passage of a cleaning tube, a valve chamber mounted on the universal joint member and on the opposite side of 25 the universal joint relatively to the chamber and having a tube aperture in communication through the chamber with the aperture in the universal joint member, a valve seat surrounding the valve chamber aperture, and an automatically closed valve on 30 said seat adapted to be opened by the tube on its insertion.
10. A surface condenser having a series of tubes and a chamber outside the tube ends, the outer wall of said chamber having a 35 series of openings, a universal joint member in each of said openings having an aperture for the passage of a cleaning tube, a valve chamber mounted on the universal joint member and outside of the universal joint and having a tube aperture in communication through the chamber with the aperture in the universal joint member, a valve seat surrounding the valve chamber aperture, an automatically closed valve on 40 said seat adapted to be opened by the tube on its insertion, and a movable cover outside the valve chamber for securely closing the tube aperture.
11. A surface condenser having a series of tubes and a chamber outside the tubes, the outer wall of the chamber having an opening, a universal joint member in said opening and having an aperture for the passage 45 of a cleaning tube, a valve chamber mounted on the universal joint member and outside of the universal joint and having a tube aperture in communication through the chamber with the aperture in the universal joint member, a valve seat surrounding the valve chamber aperture, and a valve on the opposite side of the universal joint relatively to the chamber adapted to be opened by the insertion of the cleaning tube and automatically closed on the withdrawal of the tube to prevent the escape of water from the aperture.
12. A surface condenser having a series of tubes and a chamber outside the tubes, the outer wall of the chamber having an opening, a universal joint member in said opening and having an aperture for the passage of a cleaning tube, a valve chamber mounted on the universal joint member and outside of the universal joint and having a tube aperture in communication through the chamber with the aperture in the universal joint member, a valve seat surrounding the valve chamber aperture, and an automatically closed valve on said seat adapted to be opened by the tube on its insertion.
13. The combination with the water tubes and circulating water chamber of a surface condenser, the outer wall of the water chamber being provided with an opening, of a cover for the opening forming a water-tight joint with the chamber wall, a universal joint member mounted in said cover and forming a water-tight joint with the cover and having an aperture for the insertion of a cleaning tube for delivery of cleaning fluid to the tubes, said aperture being adapted to be closed by the tube on its insertion into the water chamber to prevent the flow of water through said aperture, and means for closing the aperture to prevent the flow of water when the cleaning tube is withdrawn.
14. The combination with the water tubes and circulating water chamber of a surface condenser, the outer wall of the water chamber being provided with an opening of a universal joint member mounted in said opening and having an aperture for the insertion of a cleaning tube and forming a water-tight joint with the chamber wall, a cleaning tube adapted to be inserted through said aperture in the universal joint and to prevent substantial flow of water through said aperture, and a valve on the opposite side of the universal joint relatively to the chamber adapted to be opened by the insertion of the cleaning tube and automatically closed on the withdrawal of the tube to prevent the escape of water from the aperture.
15. A cleaning device, consisting of a cap adapted to close an opening in a condenser wall, a universal joint member mounted in said cap and forming a fluid-tight joint therewith and having an aperture for the insertion of a cleaning tube, a cleaning tube adapted to be inserted through said aperture and to prevent substantial flow of fluid through said aperture, and a valve on the opposite side of the universal joint relatively to

- the chamber for closing said aperture adapted to be opened by the insertion of the cleaning tube and automatically closed on the withdrawal of the cleaning tube.
- 5 16. A cleaning device, consisting of a cap adapted to close an opening in a condenser wall, a universal joint member mounted in said cap and forming a fluid-tight joint therewith and having an aperture for the insertion of a cleaning tube, a cleaning tube adapted to be inserted through said aperture and to prevent substantial flow of fluid
- 10
- 15
- 20

through said aperture, a valve on the opposite side of the universal joint for closing said aperture adapted to be opened by the insertion of the cleaning tube and automatically closed on the withdrawal of the cleaning tube, and a cover for securely closing the outer end of the aperture when the cleaning tube is withdrawn.

In testimony whereof, I have hereunto set my hand.

WILL H. PHILLIPS
